W. FRENIER.
WHEEL CLAMP,
APPLICATION FILED FEB. 17, 1916.

1,240,836.

Patented Sept. 25, 1917.

UNITED STATES PATENT OFFICE.

WILLIAM FRENIER, OF CORLISS, WISCONSIN.

WHEEL-CLAMP.

1,240,836.

Specification of Letters Patent. Patented Sept. 25, 1917.

Application filed February 17, 1916. Serial No. 78,804.

To all whom it may concern:

Be it known that I, WILLIAM FRENIER, a citizen of the United States, and resident of Corliss, in the county of Racine and State 5 of Wisconsin, have invented new and useful Improvements in Wheel-Clamps, of which the following is a description, reference being had to the accompanying drawings, which are a part of this specification.

10 The invention relates to wheel-clamps.

The invention further relates to wheel-clamps used in combination with a lifting means.

15 The invention is designed more particularly to provide an apparatus for facilitating the replacement of bearing members in the journal boxes of railway cars with the least time and danger to the operator.

Under present conditions of railroading 20 when a bearing member, or "brass" as they are called, has to be replaced in a car-wheel bearing, the car is generally side tracked and left there to be repaired. It may be some time before the repair crew reach the 25 car and during the meantime the car may have been broken into. My invention has for its object to provide a device whereby the bearing members or brasses may be replaced in a few minutes while the cars are 30 on the right of way. Under the old method of replacing a brass the wheel and axle were held against movement by blocking and then the bearing was relieved of the weight of the car by blocking and jacking between the 35 ground and the car body. This was the general method pursued before a car was in condition to have the bearing replaced. Such a method not only took time but subjected the workmen to continual danger as 40 they had to work beneath the car while blocking it up and there was constant danger of the blocking giving way while they were replacing the bearing.

In order to obviate these difficulties I have 45 devised a simple form of wheel clamp which practically does away with blocking. This clamp has a bearing portion and a wheel engaging portion adjustable with respect to the bearing portion so that the bearing portion may be disposed in a substantially horizontal plane substantially parallel to the axle of the car for receiving a lifting means,

and the wheel engaging portion be positioned to engage the flange or ball of wheels of different types. When so positioned the 55 lifting means, such as a jack, is placed upon the bearing portion and its head brought up into position beneath the journal box or truck frame and the weight of the car acting downwardly through the jack bears upon 60 the bearing portion and thus exerts a force upon the clamp to maintain the wheel against movement on the rail and more particularly from raising from the track when the body of the car is raised. When the 65 bearing has been relieved of the weight of the car it may be readily replaced.

While my clamping device has particular application in railroad work it is also well adapted for use in removing and replacing 70 springs on automobiles, as the wheel or wheels of the vehicle may be secured against movement and the jacks or other lifting means then manipulated to lift the body of the vehicle from the springs and wheels 75 after which the springs may be readily removed, repaired and replaced.

The invention is further designed to provide a wheel clamp which is disposed at the 80 side of the railway car or other wheeled vehicle whereby it is not necessary to go beneath the car in using the device and the liability for accident thus avoided.

The invention is further designed to provide a new and improved form of wheel 85 clamp which when used with a lifting device provides an efficient means for lifting a vehicle body or member carried by the vehicle from its wheels and axle or its frame.

The invention is further designed to provide a new and improved form of wheel 90 clamp.

In the drawings:

Figure 1 is an elevation view of the device showing it applied to a railroad car;

Fig. 2 is a section taken on the line 2—2 of Fig. 1;

Fig. 3 is a plan view of the device;

Fig. 4 is a section taken on the line 4—4 of Fig. 3;

Fig. 5 is a detail view of the bottom of the device;

Fig. 6 is a section taken on the line 6—6 of Fig. 4.

In general the device comprises a base or supporting member 7 and a clamping means connected thereto which under a force acting upon the base member secures the wheel 5 against movement.

The base member 7 consists of a flat slab or platform preferably of wrought metal, having gripping ribs 7' and a marginal upstanding rib around its edge on the top 10 thereof and reinforcing ribs 8 on the bottom thereof which form a plurality of compartments or recesses 9, sharpened projections 10 on the edge of said ribs for gripping the surface upon which the member rests, a handle 15 11 pivotally mounted within the plate adjacent one end thereof and adapted to be moved into a recess 12 in the plate so as to preserve the continuity of the upper surface of the plate, and upright members or standards 13 integral with the plate and disposed adjacent one end thereof. The ribs 8 facilitate the use of the device on sandy or soft ground. The base member 7 provides a substantial bearing area over which the force of 25 the load may be distributed and is of a width which enables it to be used between two ties if desired.

The means for securing the wheel of the car or vehicle against movement includes a 30 holding or clamping member 14 mounted intermediate its end on a pin 15 journaled in the uprights 13 and means for securing said member 14 in various positions of adjustment. The adjustable connection between 35 the base and the clamping members is very important first because in order to secure the best results the base should be disposed in a substantially horizontal plane substantially parallel with the car axle so that the lifting 40 device will be disposed substantially vertical to insure its efficient action and prevent its slipping due to any inclination of the base from a substantially horizontal plane and second because the device should be capable 45 of use on different kinds and constructions of car wheels. To this end the clamping member is pivotally connected to the supporting member and is capable of being adjusted relative thereto. The clamping member 50 14 is provided with a projecting holding arm or clamping finger 17 which extends outwardly from the pivot and is adapted to engage the ball of the car wheel 18 or the rim of a vehicle wheel and said member is also 55 provided with a segmental lock portion 19 which extends below the pivot substantially at right angles to said holding arm and is provided with a plurality of apertures 20 spaced apart on an arc taken a predetermined distance from the pivot point of said member and with a plurality of notches 21 staggered in relation to apertures 20 and spaced apart on the periphery of the segment. Thus the device consists of a two 60 65 part member provided with means for securing

ing said parts in different positions of adjustment with respect to each other for the reasons given above.

The means for securing the member 14 in various positions of adjustment comprises 70 a locking pin 22 which is adapted to be inserted in either pair of aligned apertures 23 and 24 in the uprights 13. When said pin is inserted through the apertures 23 it is in line with the row of apertures 20 and is 75 passed through one upright, one of the apertures 20 and then through the other upright. When said pin is inserted through the apertures 24 it is in line with the row of notches 21 and is passed through one upright one of 80 the notches and through the other upright. Thus the pin serves to maintain the member 14 against movement with respect to the uprights and base in various positions of adjustment. A flexible connection, such as a 85 chain 25, is secured to the pin 22 and to an eyed portion 26 of the base 7.

Means are also provided for preventing lateral movement of the member 14 between the uprights 13 comprising segmental ribs 90 27, the edges 28 of which slidably engage the inner sides of the uprights 13.

It will also be noted that the holding finger 17 of the member 14 projects beyond the end of the base 7 so that the base plate may 95 be placed adjacent the outer side of the wheel to be secured and it will not be necessary to go beneath the car.

With the construction above described the base plate is disposed adjacent the side 100 of the wheel to be clamped and the member 14 is adjusted and moved so as to bring the finger 17 into engagement with the ball of the wheel 18. Then the pin 22 is placed in either of the apertures 24 or 23 most suitable and through that notch 21 or aperture 20 which is most suitable to secure the wheel against movement. Thus the wheel 18 is disposed between the holding finger 17 and the rail 30 and will be held against movement by means acting downwardly on the wheel clamp.

The means for lifting the weight of the car from the axle 31 may be any suitable means connected or unconnected with the 115 wheel clamp and in the present instance I have shown a common form of lifting jack A comprising a base 32 having a threaded bore for receiving the threaded lifting bar 33 provided with the usual movable head 120 35 and a collar 36 provided with apertures 37 through which any suitable bar may be inserted to turn the bar 33 with respect to the base 32 to raise or lower said bar 33 and head 35.

In the present instance the jack A simply rests on the base plate 7 so that it may be moved to various positions upon the base to accommodate different constructions of cars as the truck frame and axle of differ- 125 130

ent types of cars extend outwardly at different distances from the wheels. Though I have shown the lifting jack as resting on the plate 7 it will be obvious that it may be movably secured thereto without departing from the scope of this invention. With the present construction, however, the usual lifting jack provided by the railroads may be used.

- 10 With the construction above described when it is desired to replace a brass in a car all that is necessary is to place the wheel clamp device in position adjacent the side of the car wheel and so that its supporting portion is in a substantially horizontal plane. Then the member 14 is brought down into engagement with the ball of the wheel and locked in this position. The lifting means such as the jack A is placed at the desired position upon the support 7 and the lifting bar 33 turned or moved to bring the head 35 up into engagement with a portion of the journal box 34 or the truck frame 37 mounted on the car B and on a further turning of the bar 33 the journal box or truck frame is raised with the car B so as to relieve the wheel 18 and its axle 31 of the weight of the car after which the cover 39 of the journal box is lifted up or removed and the brass 40 resting on the upper side of the axle 31 may be replaced without any fear of injury to the operator. As the lifting means is mounted on the platform or support 7 the force exerted by the weight of the car will act downwardly through the lifting means and upon the support and thus maintain the support and its holding member in fixed position and this force will be transmitted against the ball of the wheel 40 and the wheel thus held to the rail against movement and the axle held in position. Thus I utilize the force of gravity due to the weight of the car to counteract the upward force on the wheel and axle due to the lifting of the car body therefrom. It will also be noted that as the adjustable connection between the parts of the clamp permit of the horizontal disposal of the supporting platform for the jack the force due to the weight of the car is distributed over the platform which is of a sufficient size to give a good bearing area but at the same time is light enough to be easily carried about by one man. Thus by the arrangement of the parts, as described, I dispense with any special means for securing the wheel clamp to a fixed support and provide a clamp which may be leveled by the positioning of its own parts.
- 50 With the construction above described the brass may be replaced on a car within the station or out on the right of way and the mechanism is so simple that it may be operated by unskilled labor and the old method of blocking is practically done away with.
- 55 Furthermore owing to the arrangement of the parts the device may be sufficiently light as to be carried around by one man and it may be made at a cost which will enable the railroads to provide every train crew with one of them.
- 60 In the case of the use of the device in connection with other wheeled vehicles, such as automobiles, the wheel is clamped against movement on its support and the body of the vehicle then lifted up to relieve the springs of its weight after which the springs may be readily repaired, removed, or replaced. The device may also be used to hold the wheels in position to permit the straightening of the axles of the wheels.
- 65 The invention thus exemplifies a new and improved form of wheel clamp which owing to its adjustability can be used on all types of cars or vehicles for the purposes described.
- 70 The invention is not to be restricted, unless necessary, to the details of construction herein set forth as it is my intention to claim the same as broadly as will be permitted by the state of the art.
- 75 The marginal upstanding rib around the top edge of the base provides a holding means for the jack to prevent its slipping from the base should the base be placed in an inclined position. This allows the jack to engage the journal box slantly to push it laterally as well as lift it. This position of the jack is often necessary to release the brass. Furthermore it has been found to be important to locate the locking means below the pivotal point, so that at all times it is accessible and free from obstruction by the car structure. In other words, it matters not how close the holding finger is placed below the journal box and its retaining straps, the lock will not be obstructed.
- 80 Another important feature is the staggered arrangement of the locking apertures and notches. This provides a maximum number of fine adjustments in a short length of locking portion and at the same time allows the use of a locking pin of relatively large diameter. A still further important feature of the device is secured by depending on the locking portion below the pivot. As thus constructed the jack can oftentimes be placed to engage the depending lock portion and will serve to retain the clamping finger in locked position without the use of the locking pin. This is especially advantageous should the pin become detached from the base and be lost.
- 85 What I claim as my invention is:
- 90 1. A wheel clamp comprising a platform adapted to support a jack, a wheel holding member having a hooked wheel engaging portion and a segmental notched portion provided with a plurality of apertures pivotally carried by said platform, and a lock-
- 95 100 105 110 115 120 125 130

- ing pin adapted to engage with any of the notches or apertures in said segmental portion and be secured to said platform to lock said wheel holding member to said platform.
2. A wheel clamp, comprising a supporting member, a wheel holding member pivotally connected thereto, said members being provided with a plurality of sets of pin engaging means arranged in staggered relation to each other, and a locking pin adapted to engage either set of said pin engaging means for adjustably securing said members against movement with respect to each other.
3. A wheel clamp, comprising a supporting member having a relatively flat horizontally disposed platform to removably support a lifting device, a wheel holding member pivotally connected at one edge of said platform, and a locking means for said pivotal member to secure it in adjusted positions and located below the pivotal axis of said member.
- 25 4. A wheel clamp, comprising a platform having a wheel holding member pivoted thereto and provided with a lock portion extending below its pivot and a projecting holding arm extending outwardly from its pivot substantially at right-angles to said lock portion, and a locking means for engaging said lock portion adjacent to said platform to retain said holding arm rigid in respect to said platform.
- 30 5. A wheel clamp, comprising a platform having a wheel holding member secured thereto, said platform having formed on its underside a plurality of intersecting ribs to provide recesses therebetween, and pro-

jections depending downwardly from the edges of said ribs to coöperate with said recesses and ribs in retaining said platform in position.

6. A wheel clamp, comprising a platform having a wheel holding member secured thereto, said platform having formed on its underside a plurality of ribs to provide recesses therebetween and projections on said ribs, and also provided on its upper side with an upstanding marginal rib extending around the edge of the platform to retain a lifting means on said platform when placed in an inclined position.

7. A wheel clamp of the character described, comprising a platform and a wheel holding member mounted for vertical adjustment adjacent to one edge of said platform, said platform being constructed to support a lift-jack for horizontal adjustment independent of said wheel holding member, and said wheel holding member comprising a bifurcated supporting member, a clamping member pivoted in the bifurcation of the supporting member and provided with a clamping finger and notches formed concentric with its pivot, and a locking means for retaining the nose of said clamping finger in its adjusted positions and with the nose located either above or below the pivot of the clamping member, 70 said locking means embodying a pin rigidly and removably supported by both arms of the bifurcated supporting member and adapted to separately engage said notches in the clamping member.

In testimony whereof, I affix my signature.

WILLIAM FRENIER.
